Primary Examiner — Kelley A Donnelly(74) *Attorney, Agent, or Firm* — Leanne Taveggia Farrell; Westman, Champlin & Koehler, P.A.(57) **CLAIM**

The ornamental design for a display table, as shown and described.

DESCRIPTION

FIG. 1 is a front perspective view of a display table showing our new design;

FIG. 2 is a back perspective view thereof;

FIG. 3 is a front view thereof;

FIG. 4 is a back view thereof;

FIG. 5 is a right side view thereof;

FIG. 6 is a left side view thereof; and,

FIG. 7 is a top view thereof.

The broken lines shown in the drawings are included for purposes of illustrating portions of the display table and form no part of the claimed design.
